[57] CLAIM

The ornamental design of a water bottle pack, as shown and described.

DESCRIPTION

FIG. 1 is a perspective view of my design showing the front and left sides and the top in a partially open position;

FIG. 2 is a perspective view of my design showing the back and right sides and the top in a partially open position;

FIG. 3 is a bottom plan view of my design;

FIG. 4 is a view similar to that of FIG. 1, but showing the top of my design in the closed position; and

FIG. 5 is a view similar to that of FIG. 2, but showing the top of my design in the closed position.

*Fig. 1**Fig. 2**Fig. 3*

*Fig. 4**Fig. 5*
